(57) **CLAIM**

The ornamental design for a convertible laptop computer, as shown and described.

DESCRIPTION

The present application is related to U.S. Design patent application Ser. No. 29/649,420, entitled Adjustable Folio, and to U.S. Design patent application Ser. No. 29/649,425, entitled Stylus Loop, both filed concurrently herewith, the entire disclosures of which are incorporated herein by reference.

FIG. 1 is a top perspective view of the convertible laptop computer according to a first embodiment of our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a top perspective view of the convertible laptop computer according to a second embodiment of our design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top elevation view thereof;

FIG. 14 is a bottom elevation view thereof;

FIG. 15 is a top perspective view of the convertible laptop computer according to a third embodiment of our design;

FIG. 16 is a front elevation view thereof;

FIG. 17 is a rear elevation view thereof;

FIG. 18 is a right side elevation view thereof;

FIG. 19 is a left side elevation view thereof;

FIG. 20 is a top elevation view thereof; and,

FIG. 21 is a bottom elevation view thereof.

Broken lines are environmental only and form no part of the claimed design.

1 Claim, 15 Drawing Sheets
